CARBON RIBBON FEED ATTACHMENT

Donald B. Brewster, Euclid, Ohio, assignor to
Addressograph-Multigraph Corporation, Wil-
mington, Del., a corporation of Delaware

Application April 30, 1947, Serial No. 744,977

2 Claims. (Cl. 271—2.1)

1

This invention relates to carbon ribbon feeding attachments and more particularly to carbon ribbon feeding attachments of the type especially adapted to be used on printing machines through which printing devices are passed serially to a printing position in the machine where printing impressions are made from the printing devices on a continuous sheet or the like.

In the use of printing machines of the aforesaid character, it is customary to employ printing devices having a series of lines of printing characters disposed upon the printing devices from which printing impressions are made. Such printing machines are so constructed that the printing devices are withdrawn one by one from the supply magazine and are advanced in a step-by-step manner to a printing position in the machine. At such printing position, a sheet or form is disposed in the desired relationship to the printing device and while the printing device remains stationary at printing position a suitable impression means is operative to make the desired printing impressions from the type characters of the printing device on to the sheet.

In certain types of printing machines wherein it is desired to make more than one copy of the printing characters during each printing impression, a plurality of sheets or forms are positioned in the machine one above the other and carbon paper or other suitable transfer material is placed between the adjacent sheets so that upon the making of a printing impression upon the lowermost sheet a corresponding impression is transferred from the carbon sheets to each of the plurality of sheets or forms. One method, more or less commonly used heretofore to make duplicate copies in printing machines, has been to use pads of sheets or forms containing, as an integral part thereof, carbon papers interleaved between the various sheets or with transfer material coated on the reverse side of each of the sheets. However, this is somewhat wasteful procedure inasmuch as only a small portion of the transfer material is ordinarily used. Another method of placing transfer material between interleaved sheets, which has been commonly used heretofore, is to insert a plurality of carbon ribbons or carbon sheets between the plurality of forms in such a manner that the carbon sheets extend therebetween transversely to the forms at the printing position. This entails feeding the carbon sheets transversely to the plurality of forms periodically during the operation of the machines so that fresh or unused portions of the sheets are presented in transfer position during

2

each printing operation. In this connection, it is a primary object of my invention to feed carbon sheets or ribbons of this character in a novel manner.

5 It is a further object of my invention to enable carbon sheets or ribbons to be fed between a plurality of sheets or forms transversely thereto and in a novel and expeditious manner by a source of power independent of the operating 10 means of the printing machine and in timed relation to the operation of the printing machine.

Other and further objects of the present invention will be apparent from the following description and claims and are illustrated in the 15 accompanying drawings which, by way of illustration, show preferred embodiments of the present invention and the principles thereof and what I now consider to be the best mode in which I have contemplated applying these principles. Other embodiments of the invention embodying 20 the same or equivalent principles may be used and structural changes may be made as desired by those skilled in the art without departing from the present invention and the purview of 25 the appended claims.

In the drawings:

Fig. 11 is a wiring diagram showing certain 55 aspects of the timing of my novel attachment.

3
General description

In the form chosen for disclosure in the drawings, my invention is embodied in a printing apparatus comprising a machine 20 adapted to impress information from printing devices onto a plurality of forms or sheets F which, in the embodiment of my invention shown in the accompanying drawings, are fed from a supply shelf S through the printing machine 20 by a form feeder attachment FF. An understanding of the specific construction of the form feeder attachment FF is not necessary to a complete understanding of my invention, and it will be noted that other suitable types of form feeders, well known to those skilled in the art, may be used in machines embodying my invention. However, for the purpose of disclosing my present invention, it will be noted that a plurality of elongated sheets or forms F having perforations 25 formed along their lateral edge portions, are stored in folded position on a shelf S and are fed therefrom through the printing machine 20 by the form feeder attachment FF, which has rotary members therein engageable in the perforations 25 and is effective to feed the forms F through the machine 20 in a positive manner and in timed relation to the printing operations of the machine.

While the particular form and arrangement of the printing machine 20 is in many aspects of the present invention immaterial, the particular printing machine 20 which is herein shown is of the type wherein a series of individual printing devices such as, for example, printing devices of the character disclosed in the Gollwitzer Patent No. 2,132,412, patented October 11, 1938, each bearing printing means thereon, are advanced one by one from a supply means, such as an upstanding magazine M, to a printing position provided in the machine. The printing position may in the present instance be considered as being defined as part of an impression means such as the platen mechanism P. The magazine M is supported on a printing machine frame 22 which in the form herein shown is generally desk-like in character so as to provide two end walls 24a and 24b, and a table-top T upon which sheets, forms and the like may be supported beneath the platen mechanism P for the performance of the printing operations thereon. In the operation of the printing machine 20, the printing devices are withdrawn one by one from the bottom of the upstanding magazine M and are advanced in a step-by-step manner along a suitable feed path beneath the table-top T, until each printing device comes to rest at printing position beneath a window or opening W formed in the table-top T. It is while the printing device is at rest at printing position that the platen mechanism P is operated to produce a printing impression from the type characters embodied in the printing device. After one or more printing operations have been performed thereon or therefrom, the printing device is further advanced so as to be discharged into a collector means such as a drawer K. The form and construction of the printing machine 20 will be described herein only insofar as it is directly related to the attainment of the desired feeding of carbon ribbon or other transfer material therethrough, and for further details of construction and operation of the printing machine 20 reference may be had to the Hueber Patent No. 2,359,850, patented October 10, 1944.

When a printing device is located in printing position, the lines of type characters are disposed parallel to the forward edge 23 of the printing

5 machine frame 22 with the upper or first line of such type characters located close to the rear edge of the printing machine frame. Hence in the performance of a printing operation the individual form of the form sheets on which the printing operation is to be performed is located with its top edge closest to the rear edge of the printing machine frame. The form F shown in Fig. 1 of the drawings comprises a plurality of elongated sheets 10 which are stacked in alignment with each other and have perforations 25 formed along the longitudinal edge portions thereof.

15 A control mechanism K, Figs. 9 and 10, is embodied in the printing machine 20, and affords means by which my novel carbon ribbon feed attachment is operated to feed carbon ribbon or like transfer material through the machine 20 in timed relation to the printing operation of the machine, as will be discussed in greater detail 20 hereinafter.

The printing machine

25 The printing machine herein illustrated is of the type wherein an impression means is provided by the platen mechanism P, and this platen mechanism is supported in an operative relationship upon the table-top T by means of a printing frame 50, the specific construction of which is illustrated and described in the Hueber Patent 30 No. 2,275,439, patented March 10, 1942. The printing frame 50 is in the present case disposed so as to project upwardly from the table-top T at a point located a considerable distance rearwardly and to the right of printing position, and the 35 printing frame extends forwardly at an angle of substantially 45° with respect to the forward edge 43 of the printing machine frame, thereby to locate the forward end of the printing frame 50 directly above the printing position. The magazine M is located just to the right of the vertical 40 extending portion of the printing frame 50 and the printing devices are advanced from the bottom of the magazine M in a forward direction and then along a suitable guide path beneath the table-top T and to printing position. The particular arrangement and construction of the 45 printing device advancing path is discussed in the aforesaid Hueber Patent No. 2,359,850.

50 The platen mechanism P is herein illustrated as being of the form which is incorporated in the printing machine shown in the aforesaid Hueber Patents Nos. 2,275,439 and 2,359,850 and this platen mechanism is described in detail in the Hueber Patent No. 2,359,849. The platen mechanism P comprises a carriage PC supported for 55 reciprocation in a direction from front to rear in the printing machine along a guideway provided beneath a head 52 mounted at the forward end portion of the printing frame 50, and a platen roller PR is supported on, and carried by, 60 the carriage PC. The platen roller PR is arranged in a horizontal position at right angles to the path of reciprocation of the carriage PC, that is, parallel to the forward edge 23 of the printing machine frame 22. The platen roller PR is supported by means such as toggles so that the 65 platen roller may be shifted from a normally elevated or inactive position to a lower or active position wherein the platen roller may be effective to press a sheet or form, such as the form F, into printing cooperation with a printing device disposed at printing position. The platen mechanism P in the form herein discussed is arranged so that the platen roller is in its elevated or inactive position when the carriage PC is at its 70 rearward or at rest position shown in Fig. 1 of

the drawings. When a printing operation is to be performed the carriage PC is guided in a forward direction through an idle stroke by means of actuating mechanism indicated generally at 55 in Fig. 1 of the drawings, and in the course of such forward movement of the carriage PC the toggle means are guided to shift the platen roller PR to its lower or active position. The platen roller PR reaches its lower or active position at substantially the time when the forward stroke of the carriage PC has been completed and the toggle means is then latched so as to maintain the platen roller in its lower or active position during the return or rearward stroke of the carriage PC. Hence during the rearward or active stroke of the carriage PC the platen roller PR may be rolled across the form F to effect the desired printing operation. As the platen roller approaches the rear end of its stroke and has completed the desired printing operation, it is withdrawn to its elevated or inactive position so that the form feeder mechanism FF may be actuated, during the first part of the next printing cycle of operation, to feed an unprinted portion of the form F into printing position, at which time my novel carbon ribbon feed attachment is also actuated to effect feeding of carbon strips B transversely to the direction of movement of the forms F.

Carbon ribbon feed attachment

The carbon ribbon feed attachment C shown in the accompanying drawings comprises a reel supporting mechanism 60 and a carbon ribbon feed attachment 62 carried by a supporting bar 64 which is mounted on the head 52 of the printing frame 50 in a manner which will be described in greater detail presently. The carbon ribbon feed mechanism 62, as will be discussed in greater detail hereinafter, is effective during the operation of the printing machine 20 to intermittently withdraw sheets of carbon ribbon B in a step-by-step manner from reels R carried by the reel supporting mechanism 60, and feed the sheets of carbon B so withdrawn from the reels R transversely between the forms F, and at an angle thereto, through the printing position. The intermittent feeding of the carbon sheets B is accomplished in timed relation to the operation of the printing machine 20 so that a fresh portion of the carbon sheets B is placed in printing position for each printing operation.

The support bar 64 is attached to two sleeves 66 and 67 by two bolts 69 and 70, respectively. The bolts 69 and 70 extend through slots 72 and 73 formed in the support bar 64 so that the support bar 64 may be adjusted in a longitudinal direction relative to the sleeves 66 and 67. The sleeves 66 and 67 are mounted on two rods 75 and 76 respectively and are secured thereto by any suitable means such as for example, bolts 78, Fig. 1. The rods 75 and 76 are attached by bolts 80 to a shelf 82 supported above the head 52 of the printing frame 50. Thus, three bolts as 84, disposed in substantially triangular relation one with the other, are secured to and extend upwardly from the head 50. Nuts as 84' on the bolts 84 are disposed beneath the shelf 82 so that it rests thereon and by adjusting the position of these nuts on these bolts, the apparatus supported by the shelf 82 may be raised or lowered and the angular position thereof may be varied so that the shelf 82 may be leveled or otherwise adjusted. The nuts 84" on the bolts 84 engage the top of the shelf 82 and hold it against displacement.

The carbon ribbon reel supporting mechanism 60 comprises a substantially U-shaped mounting bracket 86, Figs. 1, 2 and 3, having a bottom wall 88 and two upstanding side walls 90 and 91. In the machine shown in the accompanying drawings four spindles or shafts 93, 94, 95 and 96 are mounted in and supported by the side walls 90 and 91. Four reels R₁, R₂, R₃ and R₄ are journaled on the spindles 93, 94, 95 and 96, respectively, each of the reels R₁—R₄ having a supply of carbon ribbon B wrapped thereon. A shaft 101 mounted between the side walls 90 and 91 of the mounting bracket 86 is secured thereto by a bolt 103 and a screw 104, and an idler roller 100, under which carbon paper B can be fed from the reels R₁—R₄ to the feed mechanism 62, is journaled on this shaft.

A plurality of fingers 106, 107, 108 and 109 are pivotally mounted on brackets 110, 111, 112 and 113, respectively, which are attached to the side wall 90 by any suitable means such as bolts 98. A plurality of tension springs 115, 116, 117 and 118, having one end portion attached to a corresponding respective bracket 110, 111, 112 and 113 and the other end portion attached to the corresponding finger 106, 107, 108 and 109 urge the fingers in a clockwise direction, as viewed in Fig. 3, into engagement with the carbon ribbon B carried by the reels R₁—R₄, respectively, to thereby retard rotation of the reels R₁—R₄ so as to keep the carbon ribbon B properly tensioned as it is withdrawn from the reels R₁—R₄ by the feed mechanism 62.

The carbon ribbon feed mechanism 62 comprises a mounting bracket 120 attached to the supporting bar 64 by bolts 122. Two coupling members 124 and 125, Figs. 7 and 8, are attached to the mounting bracket 120 by bolts 127 and 128, screwed into one end portion of the coupling members 124 and 125, respectively, and the coupling members 124 and 125 have threaded reduced end portions 130 and 131, respectively, which extend through a wall or supporting member 132 and are screwed into end portions of two supporting shafts 134 and 135, respectively. Thus, it will be seen that, as is shown in Figs. 7 and 8, the bolt 127, the coupling member 124, and the supporting shaft 134, form in effect a unitary shaft, and the bolt 128, coupling member 125 and the supporting shaft 135 form in effect a second unitary shaft, these two unitary shafts forming attaching members by which the supporting member 132 is supported from the mounting bracket 120.

A ratchet wheel 137, Fig. 8, is rotatably mounted on the shaft 135 adjacent to the supporting member 132, and a corrugated roller 138, which comprises a driving roller for the carbon feed mechanism, is also rotatably mounted on the shaft 135 and is attached to the ratchet wheel 137 for rotation therewith. A washer 140 mounted on the outer end portion of the shaft 135 and secured thereto by a screw 141 is effective to hold the roller 138 and the ratchet wheel 137 in position on the shaft 135.

A lever arm 143, Figs. 4 and 7, is pivotally mounted on the shaft 134 at a point substantially midway between the ends of the shaft 134, Fig. 7, the shaft 134 extending through an opening 144 formed in the lever arm 143. A rod 146, which is substantially parallel to the shaft 134, extends through an opening formed in the lower end portion of the lever arm 143 and is held in longitudinally fixed position by any suitable means such as welding. The two end portions

of the shaft 134 are somewhat reduced in cross section, and two links 148 and 149 are mounted thereon and are held in position by the supporting member 132 and a screw 151, respectively. The end portions of the rod 146 are mounted in the respective links 148 and 149, Figs. 4 and 7, and thereby hold the lever arm 143 in its mid position longitudinally of the shaft 134. A roller 155, having corrugations formed in the periphery thereof complementary to the corrugations formed in the roller 138, is journaled between the lower end portions of the links 148 and 149 and is thereby supported from the lever arm 143. A spring 157 having one portion attached to the supporting member 132 and the other end portion attached to the lever arm 143 urges the lever arm 143 in a counterclockwise direction, as viewed in Fig. 4, about the shaft 134 so that the roller 155 is normally urged toward the roller 138, in which position the complementary corrugations on the periphery of the respective rollers 138 and 155 interlock to afford good driving engagement between the driving roller 138 and the driven roller 155.

An idler roller 100a, similar to the idler roller 100, is journaled on a shaft 101a carried by the supporting member 132. This idler roller 100a is effective to guide the carbon ribbons B, withdrawn from the reel supporting mechanism 60 during the operation of my novel apparatus, into the space between the rollers 138 and 155 of the carbon ribbon feed mechanism 62.

A carbon ribbon guide plate 159 having a substantially vertically extending side flange 160 is mounted on and attached to the upper surface of the lever arm 143, and acts as a guide member for the free end portion of the carbon ribbon B fed outwardly from the feed mechanism 62 by the rotation of the feed rollers 138 and 155 during the operation of my novel apparatus, as will be discussed in greater detail presently. This plate terminates in a depending guide flange 162 which also serves as a handle or finger grip 162 to afford a readily accessible member for pivoting the lever arm 143, and therefore, the guide plate 159 in a clockwise direction about the shaft 134, as viewed in Fig. 4, to thereby move the roller 155 away from the roller 138 during the insertion of the carbon ribbon B into feeding position between the rollers 138 and 155.

The mechanism for rotating the driving roller 138, during a carbon ribbon feeding operation of the feed mechanism 62, comprises a pawl 164 pivotally mounted on a pin 166, which pin extends through the lower end portion of a link 168 and the upper end portion of a lever arm 170 rotatably mounted on the reduced end portion of the coupling member 125, Figs. 4 and 8. A torsion spring 172 carried by the link 168 engages one end portion of the pawl 164 and urges the other end portion thereof into operative engagement with the teeth formed on the periphery of the ratchet wheel 137. The upper end portion of the link 168 is pivotally attached by a pin 174 to a link 176, one end of which is pivotally attached to the supporting member 132 by a pin 178 and the other end of which is attached by a pin 180 to the plunger 182 of a solenoid 183. The solenoid 183 is mounted between brackets 185 which have feet 186 attached by screws 188 to a suitably insulated mounting plate 190 mounted on the supporting member 132 and attached thereto by screws 191.

Two switches 193 and 194, Fig. 11, are connected in series with each other and with a suitable power source, such as a battery 196, and

the solenoid 183 by wires or conductors 198, 199, 200 and 201. The switches 193 and 194 being in series with each other, it will be apparent that both switches must be closed to close the circuit between the battery 196 and the solenoid 183. This latter feature forms a part of the timing mechanism for the solenoid 183 as will be discussed in greater detail hereinafter.

It will be apparent to those skilled in the art that closure of the contacts of both of the switches 193 and 194 will cause energization of the solenoid 183 to thereby pull the plunger 182 downwardly, as viewed in Fig. 4, and thereby cause the link 176 to be pivoted in a clockwise direction about its pivot pin 178. Clockwise rotation of the link 176 causes the link 168 to be moved downwardly to thereby cause the arm 170 to be rotated in a clockwise direction, from the position indicated in solid lines in Fig. 5 toward the position indicated in broken lines therein, which thereby causes the pawl 164 to rotate the ratchet wheel 137 in a clockwise direction. Upon de-energization of the solenoid 183, the link 176 is again raised, or, in other words, rotated in a counterclockwise direction as viewed in Fig. 4, by a compression spring 203 mounted between the lower edge portion of the link 176 and the top surface of a spacing block 205 secured to the supporting member 132 by bolts 206. Upward movement of the link 176 causes the pawl 164 to slide idly over the teeth of the ratchet wheel 137 in a counter-clockwise direction, which ratchet wheel is held against counter-clockwise rotation by a detent 209 mounted on the upper edge portion of the supporting member 132 by a screw 212 and a pin 214. A substantially L-shaped bracket 208, having a vertically extending leg 210 and a horizontally extending leg 211, is attached to the spacing block by the bolts 206.

A plug 213, having an enlarged head 213a and a shank 213b is mounted in a complementary counter-sunk opening formed in the link 176, the shank 213b extending downwardly into the spring 203 to hold the upper end portion thereof from lateral displacement relative to the link 176. A stop screw 215, Figs. 4 and 6, having a knurled head 216 is screwed into the horizontal leg 211 of the bracket 208 in substantially axial alignment with the plug 213. This stop screw 215 acts as an adjustable stop member for limiting the upward movement of the link 176 by engaging the head 213a of the plug 213. The vertical position of the stop screw 215 may, of course, be adjusted by screwing it into and out of the bracket 208, and a lock nut 218 is provided on the screw 215 which may be engaged with the bracket 208 to hold the stop screw 215 in adjusted position.

Adjustment of the lock screw 215 in a vertical direction is effective to adjust the stroke through which the link 176 may be oscillated by the plunger 182 of the solenoid 183 and, therefore, is effective to adjust the throw of the pawl 164 and the amount which the pawl 164 will rotate the ratchet wheel 137 during the carbon ribbon feeding operation of my novel attachment. It will be noted that in Fig. 5, the pawl 164 is shown as having advanced the ratchet wheel 137 a distance equivalent to three teeth between the position shown in solid lines in this figure and the position shown in broken lines therein. If it is desired to advance the ratchet wheel 137 more than three teeth, my mechanism may readily be adjusted for this by screwing the stop screw 215 upwardly through the bracket 208 to thereby permit the link 176 to be raised a greater distance during its

oscillation by the plunger 182 and thereby increase the throw of the pawl 164; and if, on the other hand, it is desired to advance the ratchet wheel 137 less than three teeth the throw of the link 176 and, therefore, of the pawl 164, may be reduced by screwing the stop screw 215 downwardly through the bracket 208 to the desired position of adjustment. Thus it will be seen that by adjusting the stop screw 215, the feed roller driving mechanism may be readily adjusted through a relatively wide range of movement.

A removable housing or cover H, having an opening 217 formed therein and a pin 219 projecting inwardly from one wall thereof, may be mounted on the feed mechanism 62, with the pin 219 projecting into a complementary opening formed in one of the mounting brackets 185 for the solenoid 183, and the opening 217 encircling the stop screw 215. When so positioned on the feeding mechanism 62, the cover H may be secured in position thereon by any suitable means such as a screw 221, Fig. 6, extending through the top wall of the cover H into the horizontal leg 211 of the bracket 208.

The control mechanism K, Figs. 9 and 10, comprises a mounting bar 220 mounted in the rear end portion of the machine frame 22 between the end walls 24a and 24b thereof, and bears a bracket 222 in which is journaled a shaft 224.

As is discussed in greater detail in the Hueber Patent No. 2,359,850 and the Morse Patent No. 2,359,852, the shaft 224 comprises the main drive shaft of the printing machine 20 and is driven, through suitable clutch mechanism, by a constantly rotating pulley 226. A cam 228 is mounted on the shaft 224 and is secured thereto by any suitable means such as a screw 229. The normally open switch 193 is secured on the mounting bar 220 by screws 231 in such position that the lower contact member 233 rides on the periphery of the cam 228 during the rotation of the latter, the cam 228 being made of suitable insulating material such as fibre-board. The cam 228 has a lobe 235 formed on the peripheral edge portion thereof which is adapted to engage the contact member 233 of the switch 193 and move it into contact with the other contact member 236 thereof at a certain point in each rotation of the cam 228 with the drive shaft 224, as will be discussed presently.

For the purpose of actuating the other switch 194 of my control mechanism K in timed relation to the operation of the printing machine 20, the switch 194 is associated with and controlled by the platen mechanism of the printing machine. Thus, as is described in greater detail in the aforementioned Hueber Patent No. 2,359,850 and the Morse Patent No. 2,359,852, a rock shaft 238 is mounted in the machine 20 and is oscillated first in a counter-clockwise direction and then in a clockwise direction, as viewed in Fig. 10, upon the initiation of an impressing operation of the platen mechanism P. A lever arm 240 is connected to, and rotatable with, the rock shaft 238, and has one end portion connected to a link 242 which is horizontally mounted on a pivot pin 244 projecting from a bracket 246 carried by the mounting bar 220.

In the embodiment of my invention shown in the accompanying drawings, and as best seen in Fig. 10, the end portion of the link 242, opposite the end attached to the arm 240, is normally engaged with a push button 248 which, when so engaged, is effective to hold the contacts 250 and 252 of the switch 194 out of engagement with each other, thereby maintaining the switch in open

position. Further, it will be noted that upon movement of the link 242 to the right, as viewed in Fig. 10, a leaf spring 254 carried by the mounting bar 220 is effective to move the push button 248 to the right and thereby allow the contact 250 to close on the contact 252. Thus it will be seen that shortly after the initiation of a reciprocation of the link 242 by the platen mechanism P, the switch 194 is closed by the leaf spring 254 and remains closed until just shortly before the completion of the reciprocation of the link 242, at which time the end of the link 242 again engages the push button 248 and opens the switch 194.

15 *Operation of the carbon ribbon feed attachment*

From the foregoing it will be apparent that in the operation of my novel carbon ribbon feed attachment, reels of carbon ribbon B, or like transfer material may be placed on the spindles 93-96 of the reel supporting mechanism 60 and extended therefrom under the idler roller 100, transversely between the portions of the sheets of the form F located in printing position on the table-top T, under the idler roller 100a, between the ribbon-feed rollers 138 and 155 and onto the guide plate 159. When so extended, the carbon ribbon B is positioned to be fed transversely across the form F in a step-by-step manner by the feed rollers 138 and 155 of the feed mechanism 62 in timed relation to the actuation of the platen mechanism P of the printing machine 20 through a printing cycle of operation.

Control of the feed mechanism 62, so it is operable in timed relation to the actuation of the platen mechanism P of the machine 20, is effected by the opening and closing of the switches 193 and 194 to thereby control the actuation of the solenoid 183. Thus it will be seen that, as more fully described in the previously mentioned Hueber Patent No. 2,359,850 and the Morse Patent No. 2,359,852, upon initiation of a printing cycle of operation of the printing machine 20, the main drive shaft 224 begins a one-revolution cycle of operation and the platen mechanism P begins to move forwardly through its conditioning stroke. The movement of the platen mechanism P through its conditioning stroke is accompanied by a counter-clockwise rotation of the rock shaft 238, as viewed in Fig. 10, which causes the link 242 to be moved out of engagement with the push button 248 and permits the switch 194 to close. Shortly after the switch 194 is closed, and during the conditioning stroke of the platen mechanism P, so that the platen roller PR has not yet engaged the form F, the lobe 235 on the cam 193 rides into and out of engagement with the contact member 253 of the switch 193 and thereby causes the switch 193 to be momentarily closed and then opened again. The momentary closing and then opening of the switch 193, the switch 194 being closed, causes the solenoid 183 to be energized and then de-energized thereby causing a reciprocation of the plunger 182 and a resultant oscillation of the links 168 and 176 and the pawl 164 to thereby drive the feed rollers 138 and 155 through a ribbon-feeding rotation. During the completion of the printing-cycle of operation of the platen mechanism P the cam 228 completes its one-revolution cycle, coming to rest with the lobe 235 thereon behind the contact member 233 of the switch 193, and the link 242 completes its reciprocation, coming to rest in engagement

70 with the push button 248 in which position it

again holds the switch 194 open. This is repeated upon each printing cycle of operation of the platen mechanism P, the feeding mechanism 62 being actuated during each conditioning stroke of the platen mechanism P to feed a fresh portion of the carbon ribbon B into printing position between the individual sheets of the form F. In this connection, it will be noted that because of the switch 194 which is closed only when the link 242 is reciprocated by a printing actuation of platen mechanism P, the feeding mechanism 62 is actuated through a carbon ribbon advancing operation only when the platen mechanism P is actuated through a printing cycle of operation. This prevents wasting of carbon ribbon B which would result if the feeding mechanism 62 were allowed to feed carbon ribbon during each cycle of operation of the printing machine 20 regardless of whether or not a printing cycle of operation was to take place.

From the foregoing it will be noted that I have provided a novel carbon ribbon feeding attachment which may be readily attached to printing machines such as the printing machine 20 shown in the accompanying drawings and other types of printing machines and wherein the actuation of the mechanism is effected by a novel electromagnetic mechanism which may be readily controlled by mechanism normally associated with the printing machine 20 so that the carbon ribbon feeding attachment will be actuated in timed relation with the operation of the printing machine.

Also, it will be noted that I have provided a novel feeding attachment whereby carbon ribbon or the like may be fed in a novel and positive manner.

Hence, while I have illustrated and described the preferred embodiments of my invention, it is to be understood that these are capable of variation and modification and I therefore do not wish to be limited to the precise details set forth, but desire to avail myself of such changes and alterations as fall within the purview of the following claims:

I claim:

1. In a carbon ribbon feed attachment for use on a printing machine that has a rigid printing arm extending over and in upwardly spaced relation to the printing position of the machine, said attachment comprising a mounting shelf adapted to be secured in fixed position on the rigid printing arm of such a machine, a horizontal support bar mounted on said mounting shelf for limited adjusting movement in a horizontal plane, a reel support mounted in depending relation from one end of said bar and affording means for supporting one or more carbon ribbon reels, a ribbon guide roller mounted on the lower end of said reel support, a feed unit mounted on the other end

60

of said bar in depending relation and having a second ribbon guide roller mounted at the lower end thereof, a pair of serrated feed rolls rotatably mounted on said feed unit for rotation in normally meshed relation for drawing carbon ribbon from one or more of said reels and past said guide rollers, a ratchet wheel fixed to one of said feed rolls, a shiftably mounted pawl operatively related to said ratchet wheel for imparting rotation thereto, spring means urging said pawl to an initial position, and actuating means mounted on said feed unit for actuating said pawl against said spring means to impart rotation to said rolls.

2. In a carbon ribbon feed attachment for use on a printing machine that has a rigid printing arm extending over and in upwardly spaced relation to the printing position of the machine, said attachment comprising a mounting shelf, means carried by said mounting shelf for securing and adjusting said shelf in a rigid position on the rigid printing arm of such a machine, a horizontal support bar mounted on said mounting shelf for limited adjusting movement in a horizontal plane, a reel support mounted in depending relation from one end of said bar and affording means for supporting one or more carbon ribbon reels, a ribbon guide roller mounted on the lower end of said reel support, a feed unit mounted on the other end of said bar in depending relation and having a second ribbon guide roller mounted at the lower end thereof, a pair of serrated feed rolls rotatably mounted on said feed unit for rotation in normally meshed relation for drawing carbon ribbon from one or more of said reels and past said guide rollers, a ratchet wheel fixed to one of said feed rolls, an actuating lever mounted on said feed unit, spring means urging said lever to an initial position, a shiftably mounted pawl operatively related to said ratchet wheel for imparting rotation thereto and connected to said lever for actuation thereby, actuating means mounted on said feed unit for actuating said lever against said spring means to impart rotation to said rolls, and means mounted on said feed unit for adjusting said initial position of said lever to thereby vary the feeding stroke of the pawl.

DONALD B. BREWSTER.
